DESIGN FOR A CARD DISPLAY CABINET

Ralph J. Gelinas, Cohasset, Mass., assignor to United-Rexall Drug Company, a corporation of Delaware

Application May 3, 1945, Serial No. 119,382

Term of patent 14 years

(Cl. D80—9)

To all whom it may concern:

Be it known that I, Ralph J. Gelinas, a citizen of the United States and a resident of Cohasset, Norfolk County, Massachusetts, have invented a new, original, and ornamental Design for a Card Display Cabinet, of which the following is a specification, reference being had to the accompanying drawings forming part thereof, in which

Fig. 1 is a front elevation of a card display cabinet showing my new design;

Fig. 2 is a side elevation thereof;
Fig. 3 is a top plan view thereof;
Fig. 4 is a rear elevation thereof; and,
Fig. 5 is a perspective view thereof.
I claim:
The ornamental design for a card display cabinet, substantially as shown.

RALPH J. GELINAS.
